UNITED STATES PATENT OFFICE.

JOSEPH T. CAMPBELL AND HEYWOOD Y. BILLINGS, OF MOUNTAIN LAKES, NEW JERSEY,
ASSIGNORS TO U. S. INTERNAL COMBUSTION CO., OF NEWARK, NEW JERSEY, A COR-
PORATION OF NEW JERSEY.

SPARK-PLUG.

1,287,570.

Specification of Letters Patent. Patented Dec. 10, 1918.

Application filed October 5, 1917. Serial No. 194,844.

To all whom it may concern:

Be it known that we, JOSEPH T. CAMPBELL and HEYWOOD Y. BILLINGS, citizens of the United States, and residents of Mountain Lakes, county of Morris, and State of New Jersey, have invented certain new and useful Improvements in Spark-Plugs, of which the following is a specification.

Our invention relates to spark plugs for electrical ignition of explosive charges, as, for example, for electrically igniting explosive mixtures in the cylinders of internal combustion engines.

One object of the invention is to provide an improved spark plug which is self-cleaning by the scrubbing action of the engine gases.

Another object of the invention is the provision of a spark plug which may be used over very long intervals of time without any substantial burning away of sparking points, and which will secure highly efficient ignition action throughout long periods of use.

Another object of the invention is the provision of an interior electrode of such form as to permit the ready flow of the high tension ignition current directly to a substantially indefinitely large number of sparking regions or gaps and whereby electrical losses by dissipation or like causes are effectively prevented.

Another object of the invention is the provision of a plug having a gas chamber or recess in rear of the region where the sparks occur, of such form and of such entrance and exit that the explosion of compressed charges therein aids and accelerates the ignition of the charge in the cylinder and at the same time to effectively clean the various parts of the plug and directs the ignited charge in such direction that all danger of scoring, pitting or warping of the valves or other parts of the engine, due to impinging of said flaming charges thereon is eliminated.

Other objects and aims of the invention, more or less specific than those referred to above, will be in part obvious and in part pointed out in the course of the following description of the elements, combinations, arrangements of parts and applications of principles, constituting the invention; and

the scope of protection contemplated will be indicated in the appended claims.

In the accompanying drawings, wherein we have illustrated a preferred embodiment of our invention:

Figure 1 is a central longitudinal cross-sectional view thereof; and

Fig. 2 is a horizontal sectional view of the spark plug, taken on line 2—2 of Fig. 1.

Referring now to the drawings, wherein similar reference characters refer to similar parts, 1 indicates the shell of the spark plug, the same being of the usual cylindrical form, threaded as at 2, so that it may be screwed into a cylinder and having a shoulder 3, which with the usual gasket forms a gas tight joint with the cylinder.

The conducting member 4 of the interior electrode is preferably a rod of substantial diameter, which is insulated from the outer shell, a portion of which forms the other electrode. In the present instance this insulation consists of a portion 5 composed of layers of mica wound about the rod 4, and these windings of mica are then surrounded by a plurality of mica washers 6 firmly compressed together and confined between a shoulder 7 provided upon the rod 4, and a cap piece 8. Other forms of insulation may, of course, be employed in the relations above specified.

The insulating material 6 has preferably a lateral extension 9, adapted to be seated in an angular recess 10 in the shell 1, a washer, as at 11, preferably formed of soft metal, such as copper, being inserted in the shell 1 in advance of the insertion of the insulating material, and a bushing 12 screwed into the shell 1 may be employed to secure all the parts together, a suitable washer or washers 13 being inserted between the lower end of the bushing 12, and between it and the upper shoulder of the lateral extension 9. The washers 11 and 13 are employed to make all the parts as tight and to prevent mutilation of the insulation by the bushing 12.

Suitable provision is made for securing the cable to which the current is supplied to the spark plug, as for example in the form shown, a nut 14 is employed for this purpose, the same being threaded upon the threaded end of the rod 4. All the parts so described may be of the usual construction

and may be modified to suit different requirements.

The insulating bodies 5 and 6 are so disposed within the shell 1 that the lower ends 5 thereof terminate short of the end of the shell, and the extension 16 thereof is reduced so that within the shell 1 there is formed a chamber 17, the purpose of which will be apparent hereinafter.

- 10 The lower end of the rod 4 is formed into a hollow substantially cone-shaped extension 18, the walls of which flare downwardly and outwardly, so that the lower edge 19 terminates substantially flush with the exterior 15 surface of the shell 1. This cone-shaped extension 18 is spaced from the lower edge 20 of the shell 1 so that a spark gap is provided therebetween, the inner lower edge of the shell 1 being preferably beveled or chamfered off as at 21. A chamber 22 is formed in the lower surface of the electrode 18, and suitable openings 23 are provided, which connect the chambers 17 and 22.

We find that by constructing a spark plug 25 in substantially the manner described, at or in the neighborhood of the spark region, ignition effects are obtained of a most certain and uniform character, whereby a completely continuous metallic path for the current is provided all the way around the shell 1, the narrowest space between the electrodes being provided between the lower end of the shell 1 and the surface immediately adjacent the outer periphery of the flaring end 30 of the electrode 18.

It will be noted that the passage-way forming the spark gap between the electrodes extends laterally at substantially right angles from the longitudinal axis of 40 the spark plug. This disposition of the spark gap is of great advantage since it directs the flow of the ignited charge within the chamber 17 laterally with respect to the spark plug, whereby any impinging of the 45 ignited charge against the valves, or other parts of the cylinder is eliminated, thereby insuring these parts against scoring, pitting, or warping by the constant action of such ignited charges.

50 We have also found that a spark plug constructed substantially as above described, has a further advantage that leakage and dissipation of high tension current is greatly reduced and effective ignition obtained by 55 reason of the fact that there is no tendency of the plug to foul. This fouling is prevented by reason of the fact that the particles of carbon and other solids which usually collect on electrodes and spark plugs, 60 are not permitted to come to rest in the neighborhood of the spark gap, but are effectively blown out, inasmuch as the ignited charge within the chamber 17 sweeps out along the flaring upper surface of the 65 electrode 18, and between the edge thereof

and the lower end 20, of the shell 1, whereby those surfaces are maintained in a clean condition by the scrubbing action of said ignited charge. The provision of the apertures 23 and the electrode 18 permits a portion of the ignited charges to be projected through said apertures, whereby the lower wall of said electrode is also maintained in a clean condition.

70 It will accordingly be seen that we have provided a spark plug, which is well adapted to attain, among others, all the aims and objects above pointed out, in an exceedingly efficient manner, by reason of the construction as described, the neighborhood of the spark gap is always maintained clean, whereby effective sparks may at all times be had, and the ignited charges from the spark plug are so directed that they cannot impinge upon any part of the interior of 85 the engine, whereby the latter might be damaged.

80 As many changes could be made in this construction without departing from the scope of the following claims, it is intended that all matter contained in the above description or shown in the accompanying drawing shall be interpreted as illustrative only and not in a limiting sense.

85 Having thus described our invention what we claim as new and desire to secure by Letters Patent is:

1. A spark plug comprising an outer shell, one end of which forms an electrode, there being a chamber formed in the lower end of said shell, an inner electrode comprising a hollow cone-like member, the lower end of which lies beneath the lower end of the said shell, and is spaced therefrom to form a spark gap. 100

2. A spark plug comprising an outer shell, one end of which forms an electrode, there being a chamber formed in the lower end of said shell, an inner electrode comprising a hollow cone-like member, the lower end of which flares outwardly and lies directly beneath the lower end of said shell and is spaced therefrom to form a spark gap. 110

3. A spark plug comprising an outer shell, one end of which forms an electrode, said shell having a chamber formed in the lower end thereof, an inner electrode comprising a hollow cone-like member which flares downwardly and outwardly so that the lower edge thereof extends underneath the lower edge of said outer electrode and is spaced therefrom to form a spark gap. 115

4. A spark plug comprising an outer shell, one end of which forms an electrode, said shell having a chamber formed in the lower end thereof, a conducting rod extending through said shell and insulated therefrom, the lower end of said rod carrying a hollow substantially cone-shaped electrode, the free edge of which extends directly be- 120 125 130

neath the edge of the outer shell, and is spaced therefrom to form a spark gap, the latter comprising a narrow passage-way extending at substantially a right angle to the longitudinal axis of the spark plug.

5. A spark plug comprising an outer electrode formed of a hollow metallic shell, an insulating member extending into said shell, but terminating short of one end thereof so that a chamber is formed in one end of said shell, a metallic stem extending into said shell, and through said insulating member, the lower end of said stem being of a hollow cone-like formation, which flares outwardly underneath the lower edge of said outer electrode, so as to substantially close said chamber, a passage-way being provided between the lower end of said shell and the flared end of said electrode to constitute a spark gap, said passage-way extending in a direction substantially at right angles to the longitudinal axis of the spark plug.

6. A spark plug comprising an outer shell, one end of which forms an electrode,

there being a chamber formed in the lower end of said shell, an inner electrode comprising a hollow cone-like member the lower end of which lies beneath the lower end of said shell and spaced therefrom to form 30 a spark gap, said inner electrode being provided with an exterior chamber, and passage ways extending through said inner electrodes and connecting said chambers.

7. A spark plug comprising an outer shell, one end of which forms an electrode, there being a chamber formed in the lower end of said shell and an inner electrode comprising a hollow member the walls of which extend downwardly and outwardly so that 40 the lower end thereof lies directly beneath the end of said shell which forms the electrode and is spaced therefrom to form a spark gap.

In testimony that we claim the foregoing, 45 we have hereto set our hands, this 2nd day of October, 1917.

JOSEPH T. CAMPBELL.
HEYWOOD Y. BILLINGS.
